DARIUS C. BROWN, OF LOWELL, MASSACHUSETTS.

Letters Patent No. 77,446, dated May 5, 1868.

IMPROVEMENT IN HARNESS-FRAME FOR LOOMS.

The Schedule referred to in these Letters Patent and making part of the same.

TO ALL PERSONS TO WHOM THESE PRESENTS MAY COME:

Be it known that I, DARIUS C. BROWN, of Lowell, in the county of Middlesex, and State of Massachusetts, have invented a new and useful Improvement in Loom-Harness; and do hereby declare the same to be fully described in the following specification, and represented in the accompanying drawings, of which—

Figure 1 denotes a side elevation,

Figure 2 an end view, and

Figure 3 a transverse section of a harness-frame provided with my improvement.

After a harness has received a series of warps wound around a beam, it is customary to fasten or strap the harness to the beam preparatory to the latter and the harness being introduced into a loom. When the end bars of the harness-frame are practically inelastic, they cause the harness, when strapped to the beam, to be tangential thereto, and, as a consequence, to inconveniently project therefrom. The harness, when made and applied to the beam, is apt to be very much in the way, particularly in case of stowage of the beam with others.

The object of the invention is to enable the harness-frame, after the heddles thereof may have been supplied with warp-threads, to be bent around the curved surface of the warp-beam, or the warp wound thereon. For this purpose I make the end connection-bars of the string-bars of thin flexible and elastic metal or material, such as may be bent to conform to the surface of the warp-beam or roller, or that of the warp thereon, and thus not only effect an economy of space which would otherwise be taken up by the harness, but enable beams having harnesses so applied to them to be stowed or packed together to better advantage, as the harness will take up less room than when their end bars are inflexible or inelastic.

In the drawings, *a* and *b* *b* are the string-bars, supported by brackets *c* *c* and *d* *d*, extending from two parallel bars, *A* *B*.

The heddles made of wire are strung on the bars *a*, *b* *b* in manner as represented in fig. 3.

The brackets of one bar, *A*, are connected with those of the other bar, *B*, by means of two straight elastic metallic strips, *C* *C*, capable of being bent in an arched or curved form, so as to fit to the curved surface of a cylinder of warp when on a warp-roller.

The elasticity of the bars *C* *C* should be such that after having been bent laterally about a cylindrical surface, they will readily recover their straightness, after removal from such surface, and previous to the harness being placed in a loom.

I claim as my invention—

The improved harness or heddle-frame, as made with elastic connection-bars *C* *C*, substantially as and for the purpose specified.

I also claim the combination, with the bars *A* *B* and brackets, and string-bars supported in such brackets, of the elastic connection-bars *C* *C*, substantially as herein shown and described.

D. C. BROWN.
